US00D902187S

(12) **United States Design Patent** (10) **Patent No.:** **US D902,187 S**
(45) **Date of Patent:** **** Nov. 17, 2020**

(54) **ROBOT NAVIGATION BEACON**

(71) Applicant: **iRobot Corporation**, Bedford, MA (US)

(72) Inventors: **Nick Coleman**, Needham, MA (US); **Insun Hong**, Somerville, MA (US)

(73) Assignee: **iRobot Corporation**, Bedford, MA (US)

(**) Term: **15 Years**

(21) Appl. No.: **29/687,372**

(22) Filed: **Apr. 12, 2019**

(51) LOC (12) Cl. **14-03**

(52) U.S. Cl.

USPC **D14/230; D10/109.1**

(58) **Field of Classification Search**

USPC D10/113.1, 113.2, 114.1, 114.2; D14/230, 233, 234, 238; D21/756, 771, D21/775, 791; D32/31

CPC G01S 1/00; G01S 1/042; G01S 1/0423; G01S 1/70; G01S 1/74

(57) **CLAIM**

The ornamental design for a robot navigation beacon, substantially as shown and described.

DESCRIPTION

FIG. 1 is a front perspective view of a robot navigation beacon.

FIG. 2 is a front view of the robot navigation beacon of FIG. 1.

FIG. 3 is a back view of the robot navigation beacon of FIG. 1.

FIG. 4 is a left side view of the robot navigation beacon of FIG. 1.

FIG. 5 is a right side view of the robot navigation beacon of FIG. 1.

FIG. 6 is a top view of the robot navigation beacon of FIG. 1; and,

FIG. 7 is a bottom view of the robot navigation beacon of FIG. 1.

The broken lines illustrate environmental features that form no part of the claimed design. The dot-dash line illustrates a boundary of the claimed design.

1 Claim, 4 Drawing Sheets
